UNITED STATES PATENT OFFICE.

FLOYD J. METZGER, OF NEW YORK, N. Y., ASSIGNOR TO CALIFORNIA CYANIDE COMPANY, INCORPORATED, OF NEW YORK, N. Y., A CORPORATION OF DELAWARE.

RETORT.

Application filed August 4, 1923. Serial No. 655,643.

To all whom it may concern:

Be it known that I, FLOYD J. METZGER, a citizen of the United States, residing at New York city, in the county of New York, 5 State of New York, have invented certain new and useful Improvements in Retorts; and I do hereby declare the following to be a full, clear, and exact description of the invention, such as will enable others skilled 10 in the art to which it appertains to make and use the same.

This invention relates to the fixation of nitrogen by heating mixtures of alkali metal compounds and carbon with or without a 15 catalyzing agent in the presence of nitrogen or nitrogenous gases. The invention comprises a retort in which the reaction may be advantageously conducted, and while this retort is particularly adapted for use in the 20 fixation of nitrogen it is capable of other applications.

A method of fixing nitrogen is described in United States Letters Patent No. 1,322, 25 195 and involves the heating of mixtures of alkali metal carbonates or oxides with carbon and relatively small amounts of iron, preferably in the form of iron oxide, in the presence of nitrogenous gas. As little as two 30 per cent of iron is effective and small amounts are used to avoid filling the reaction chamber with material which does not enter into the composition of the resulting cyanide material. This cyanide material or 35 furnace product containing cyanide is treated after removal from the retort to recover cyanide or hydrocyanic acid. This 40 may be accomplished by leaching the furnace product or by treating it with carbon dioxide or other suitable agents, for example, with steam, to convert the cyanide into ammonia.

Oxygen or oxidizing agents convert cyanide at low temperatures into cyanate which is not a desirable product. At high 45 temperatures such as are present in the reaction zone and particularly in the presence of carbon, this undesirable oxidation is avoided. Heretofore much difficulty has 50 been experienced in avoiding the production of cyanate because the retorts used were so constructed that after the reaction the furnace product passed into a zone of low temperature where oxidation was possible. Consequently it has been considered 55 necessary to employ nitrogenous gases from

which oxygen and oxidizing agents have been substantially removed.

It is the object of the present invention to provide a retort in which the cyanide reaction may be carried on with nitrogenous 60 gases containing oxygen or oxidizing agents without danger of loss of cyanide by conversion into cyanate.

Further objects and advantages of the invention will be understood by reference 65 to the following specification and the accompanying drawing in which a retort embodying the invention is diagrammatically illustrated.

The object of the invention may be accomplished by the provision of a retort which is adapted to be supported in a suitable furnace and is provided with means to hold the material in the reaction zone and at the temperature thereof until the reaction is completed. The means employed should prevent contact of the furnace product with the nitrogenous gases used at a temperature lower than that at which the reaction is conducted. Provision should 70 likewise be made for the withdrawal of the furnace product at the conclusion of the reaction. To best meet these requirements an inclined retort is used, the retort being mounted in the furnace and arranged so that it may be rotated. At the lower end of the retort a plug or "plunger" is introduced at a point substantially corresponding with the wall of the surrounding furnace. This plunger prevents descent of 75 the furnace product beyond the heating zone and is provided with an inlet whereby the nitrogenous gas may be introduced to the retort. The plunger is connected preferably to the closure at the end of the retort 80 so that upon removal of the latter the plunger may be withdrawn, thus permitting a portion of the contents of the retort to be raked therefrom. Before the plunger is withdrawn the supply of nitrogenous gas 85

is shut off. The furnace product may be raked from the retort into containers which are more or less air-tight to minimize contact of atmospheric oxygen therewith. In the operation there is no contact of the furnace product with oxygen at a temperature lower than that of the reaction for a sufficiently prolonged time to permit oxidation and the production of cyanates.

Utilization of the retort as described per 110

mits the use of nitrogenous gases such as atmospheric air and particularly of gases recovered from the combustion products of the heating furnace. These combustion products contain nitrogen, a considerable proportion of carbon dioxide and some oxygen. The combustion products are scrubbed to remove the carbon dioxide which may be utilized in the separation of hydrocyanic acid from the furnace product. The remaining nitrogenous gases containing a proportion of oxygen are particularly desirable for use in the cyanide reaction. By slightly increasing the proportion of carbon in the mixture which is fed to the retort the presence of oxygen may be neutralized and by preventing contact of the oxygen in the nitrogenous gases with the furnace product at a temperature lower than that of the reaction the production of cyanate is substantially avoided.

As an example of the application of the invention it is desirable to employ a mixture of alkali metal carbonate or oxide, carbon and iron in the relative proportions of forty parts of sodium carbonate, fifty-eight parts of coke and a limited quantity of iron, preferably in the neighborhood of two per cent, for example, in the form of iron oxide. These materials are finely ground and are mixed in a suitable mixing device to ensure thorough mingling. A quantity of water is preferably added during the mixing but the amount of water is limited so that the mass is not perceptibly moist.

The mass is dried and is then introduced into the reaction chamber or retort and is there subjected to an elevated temperature ranging from 950° to 1100° C. while atmospheric air or an equivalent nitrogenous gas is passed through and in contact with the mass. The retort is substantially filled with the mixture and is rotated to ensure thorough contact of the nitrogenous gas with all of the mixture with the result that the nitrogen is fixed as cyanide. The oxygen present combines with the excess carbon and escapes with the gaseous reaction products from the upper end of the retort. During the reaction the furnace product is prevented from descending below the heating zone and is therefore continuously maintained at the temperature of the reaction. When the reaction is completed the retort is opened and the plunger is withdrawn. A portion of the charge may be raked from the retort after which the plunger is returned and sufficient material is added to the retort to again substantially fill it. The furnace product contains upward to thirty per cent of cyanide which may be recovered or converted into useful products as hereinbefore described.

In the accompanying drawing 5 indicates a furnace constructed of brick-work or other

suitable material and preferably having a refractory lining 6 enclosing a combustion chamber 7. A suitable fuel, for example producer gas, may be supplied from a gas-producer 8 through a passage 9 from which the gas is delivered through gas inlets 10 to the combustion chamber 7 where the gas is mixed with air and is burned to produce the necessary high temperature. The combustion products pass over a bridge wall 11 and are withdrawn from the chamber, preferably passing through an economizer (not shown). No surplus heat is employed in preheating the air which is mixed with the gas before combustion thereof. Reference is made to Letters Patent No. 1,322,195 above referred to for the details of this arrangement.

A tube 12, preferably of oxidation-resistant material such as an alloy containing nickel and chromium, is disposed in suitable openings in the walls of the furnace 5 to occupy an inclined position. The tube is provided with flanges 13 and 14 resting on rollers 15 and 16. The flange 14 bears against a thrust roll 17 which maintains the tube in proper position in the furnace. The tube may be rotated by means of a chain 18 engaging a sprocket 19 thereon and a sprocket 20 on a shaft 21 which may be actuated in any suitable manner.

The tube 12 is filled with a furnace mixture from the upper end which is open as indicated in the drawing. The lower end of the tube is preferably closed by a head 22 bolted or otherwise secured to a flange on the tube. To prevent the travel of the furnace mixture beyond that portion of the tube which is heated by the furnace, a plunger 23 is provided which is inserted in the end of the tube. The plunger 23 has an extension 24 with a passage 25 which communicates through a pipe 26' with a flexible pipe 26 through which the nitrogenous gas is introduced. The pipe 26' passes through a gland 28 so that the tube 12 may rotate while the pipe 26 remains stationary. The nitrogenous gas is delivered through the passage 25 to the material disposed within the tube and, as will be apparent none of the material is permitted to cool below the temperature of the reaction zone and to contact thereafter with nitrogenous gas during the operation of the furnace. Thus all of the reacting mass is held at the maximum temperature and the formation of cyanide is prevented. When the reaction is completed the head 22 and plunger 23 are removed and the furnace product is withdrawn from the tube which is ready for the succeeding operation when the head and plunger have been secured again in place.

Various changes may be made in the structure described without departing from the invention, it being essential only to provide

means to prevent descent of the furnace product during the operation beyond the heating zone.

I claim:—

- 5 1. In an apparatus of the character described, a furnace having a combustion chamber, a retort extending through the chamber and means within the retort to prevent the contents thereof from passing substantially beyond the wall of the combustion chamber, said means having a passage to convey gas to the interior of the retort and being removable to permit withdrawal of the contents thereof.
- 10 2. In an apparatus of the character described, a furnace having a combustion chamber, a retort extending in an inclined position through the chamber, and means within the retort at the lower end thereof to prevent the contents from passing substantially beyond the wall of the combustion chamber, said means having a passage to convey gas to the interior of the retort and being removable to permit withdrawal of the contents thereof.
- 15 3. In an apparatus of the character described, a furnace having a combustion chamber, a retort extending through the chamber, means for rotating the retort, means within the retort to prevent the contents thereof from passing substantially beyond the wall of the combustion chamber, said means having a passage to convey gas to the interior of the retort and being removable to permit withdrawal of the contents thereof, and stationary means to supply gas to the passage while the retort is rotating.
- 20 4. In an apparatus of the character described, a furnace having a combustion chamber, a retort extending in an inclined position through the chamber, means for rotating the retort, means within the retort at the lower end thereof to prevent the contents from passing substantially beyond the wall of the combustion chamber, said means having a passage to convey gas to the interior of the retort and being removable to permit withdrawal of the contents thereof, and stationary means to supply gas to the passage while the retort is rotating.
- 25 5. In an apparatus of the character described, a furnace having a combustion chamber, a retort extending through the chamber and a removable plunger within the retort to prevent the contents thereof from passing substantially beyond the wall of the combustion chamber, said plunger having an extension with a passage therethrough to convey gas to the interior of the retort.
- 30 6. In an apparatus of the character described, a furnace having a combustion chamber, a retort extending through the chamber in an inclined position, and a removable plunger within the retort at the lower end thereof to prevent the contents thereof from passing substantially beyond the wall of the combustion chamber, said plunger having an extension with a passage therethrough to convey gas to the interior of the retort.
- 35 7. In an apparatus of the character described, a furnace having a combustion chamber, a retort extending through the combustion chamber, means for rotating the retort, a removable plunger within the retort to prevent the contents thereof from passing substantially beyond the wall of the combustion chamber, said plunger having an extension with a passage therethrough to convey gas to the interior of the retort and stationary means to supply gas to the passage while the retort is rotating.
- 40 8. In an apparatus of the character described, a furnace having a combustion chamber, a retort extending in inclined position through the chamber, means for rotating the retort, a removable plunger at the lower end thereof to prevent the contents from passing substantially beyond the wall of the combustion chamber, said plunger having an extension with a passage therethrough to convey gas to the interior of the retort and stationary means to supply gas to the passage while the retort is rotating.

In testimony whereof I affix my signature.
FLOYD J. METZGER.
